CLAIM

The ornamental design for a cap for extrusion tubes and the like, substantially as shown and described.

DESCRIPTION

FIG. 1 is a side elevational view of a cap for extrusion tubes and the like, embodying my new design, the opposite side being a mirror image thereof;

FIG. 2 is a top plan view thereof;

FIG. 3 is a bottom plan view thereof; and

FIG. 4 is a cross-sectional view thereof, taken on line 4—4 of FIG. 2.
